UNITED STATES PATENT OFFICE.

CHARLES H. HINDS, OF NEW YORK, N. Y.

INCLOSING-CASE FOR ELECTRIC MACHINES.

SPECIFICATION forming part of Letters Patent No. 368,088, dated August 9, 1887.

Application filed March 3, 1887. Serial No. 220,590. (No model.)

To all whom it may concern:

Be it known that I, CHARLES H. HINDS, a citizen of the United States, residing at New York, in the county and State of New York, 5 have invented new and useful Improvements in Inclosing-Cases for Electric Machines, of which the following is a specification.

This invention relates to improvements in inclosing-cases for electric machines, as set 10 forth in the following specification and claims, and illustrated in the accompanying drawings, in which—

Figure 1 is a plan view of an electric machine partly broken away. Fig. 2 is a section 15 in the plane xx' , Fig. 1. Fig. 3 is a section in the plane yy' , Fig. 1. Fig. 4 is a section in the plane $x'x''$, Fig. 1. Fig. 5 is a section in the plane $x''x''$, Fig. 1.

Similar letters indicate corresponding parts. 20 In the drawings, the letter A designates a case or receptacle. A suitable lid or cover, B, closes the case. To secure tight closing a packing, C, of soft rubber or other suitable material, is placed between the cover B and case A. 25 The cover B is held in place by fastening devices consisting of hooks or clamps D, secured by screws H to a ring or support, E. The ring-support or base E has lugs F, provided with holes I, for the reception of the screws H. 30 Additional holes or attaching devices, J, may be formed in the lugs F, whereby the case A, with its contents, can be secured in any suitable place, as, for example, to the side of a room. By making the base E in the form of 35 a ring of suitable size said base E will be light and cheap of manufacture, and such ring can be made sufficiently strong to secure the cover B and case A against displacement. Pads or cushions J, of suitable material—such as soft 40 rubber—are shown between the clamps or braces D and the cover B, so as to prevent injury to the cover B.

The cover B is provided with a hole for the passage of a shaft or axle, P. Suitable attaching devices or screws, K, are also provided for the attachment of the positive and negative conductors L. The seats O of the attaching screws K are held in place by screws or attaching devices L and collars and clamps M. A 45 tube or pad, N, of suitable material—such as

soft rubber—furnishes a soft support for each seat O and screw L. Such cushions N will deaden any blow or jar that is communicated to these seats O, to the collars M, or to the screws L.

The axle P is adapted for the reception of 55 an actuating device—such as a crank, (not shown,) whereby rotation can be imparted to the axle P. The axle P is provided with a shoulder or seat, R, adapted to set against a tubular seat, Q, on the cover B or case A, as 60 the case may be. Said shoulder R and seat Q are adapted to set closely together, so that no air or moisture can pass along the seat Q or shoulder R into the interior of the machine. By properly grinding the seat Q and the shoulder R said seat and shoulder can be made to 65 set closely together. A stuffing-box or packing might be applied about the axle P to exclude air and moisture. I prefer, however, the seat Q and shoulder R fitted to one another, 70 as just described, because such seat and shoulder can be readily and cheaply produced, and because they furnish a closing which is not apt to become leaky by wear, since the rotation of the axle P tends to grind the shoulder R into 75 engagement with the seat Q. A spring, S, keeps the shoulder R in engagement with the seat Q. As seen in the drawings, one end of the axle P rests on the spring S, or on the support k of the spring S. The spring S, or its 80 support k, rests on the condenser a g of the machine.

The condenser a g is made in any well-known suitable manner—for example, of sheets or plates, a, of hard rubber or other suitable material, and of sheets, g, of tin foil or other suitable material. Posts or connections W X b d e f connect the condenser a g with the frame-plate Z. The frame-plate Z is made of suitable insulating material, such as hard rubber. 85 When the post e, Fig. 1, strikes against a suitable stop, such as a screw, L, the frame-plate Z and condenser a g are prevented from turning in the direction of arrow 1.

The generating-plate T is made of suitable 95 material—such as hard-rubber—and is connected to the shaft P. When the shaft P is revolved in the direction of arrow 1, Fig. 1, the generating plate or disk T turns with the shaft. The friction of the generating-plate 100

against the cushions V U causes electricity to collect on the conductors *c*. The conductors *c* are connected by the post *b* with one set of the plates *g* of the condenser. The post *W*, which holds the cushions V U in place, connects with the other set of the plates *g*. In the drawings each set of plates *g* is shown as consisting of but one plate; but, if desired, a greater number of plates *g* may be used in each set. The cushions V U are shown as consisting of plates or supports *V*, of suitable material—such as hard rubber—and of pieces *U*, of suitable material—such as oil-silk—secured to the supports *V*. A convenient manner of securing the supports *V* in place is by providing the supports *V* with holes and passing the posts *W X* through the holes in the supports *V*. By providing the supports *V* with suitably-shaped spring-arms *Y*, which press against the frame-plate *Z* and the condenser, such spring-arms *Y* will hold the cushions V U firmly against the generating-plate *T*. Screws or attaching devices *i* can secure the spring-arms *Y* to the cushions V U. When the shaft 25 *P* is turned in the direction of arrow 1, Fig. 1, the frame-plate *Z*, condenser *a g*, and generating-plate *T* revolve in the direction of arrow 1 until the stop or post *e* strikes a stop or screw *L*. The condenser *a g* and frame-plate 30 *Z* then remain stationary, while the generating-plate *T* continues to revolve in the direction of arrow 1. By this motion of the generating-plate *T* the condenser *a g* becomes charged with electricity. When the condenser 35 *a g* is sufficiently charged with electricity, the shaft *P* is turned in the direction opposed to that of arrow 1. The condenser, generating-plate, and frame-plate *Z* are thereby moved in said last-named direction until the posts *d f* 40 come to the position indicated by dotted lines in Fig. 1. Said posts *d f* thus come into electrical connection with the screws *L*, and with conductors *l*, connected to said screws *L*.

One of the posts—as, for example, the post 45 *d*—is in connection with one set of plates *g* of the condenser, and the other post, *f*, is in connection with the other set of plates *g* of the condenser. The contact of the posts *d f* with the stops or screws *L* thus enables the electric 50 charge to be conducted through conductors *l*, connected to the screws *K* and stops *L*. The jar caused by the posts *d e f* striking the stops or screws *L* is deadened by the cushioned seats *N*, Fig. 3, of the screws *L*, so that breakage of 55 any part is not liable to occur.

In case the clamps *D* are made of material 60 which is a conductor of electricity—such, for example, as brass—care should be taken to place the clamps *D* at as great a distance as possible from the connections or screws *K* and conductors *l*, so as to prevent improper circuits of the electric charge.

In order to enable the condenser *a g* to oscillate easily in the case *A*, a rest or shoulder, 65 *h*, Fig. 2, of smooth material, such as glass, is provided.

With regard to the case *A* and cover *B*, it should be noticed that such cases and covers have heretofore been made of hard rubber. Hard rubber is a good insulator for electricity 70 and a good electric, and is well adapted for such objects as the generating-plate *T*; but I have found that hard rubber is unsatisfactory for the case *A* and cover *B*, because of the tendency of the electric charge of the machine 75 to accumulate on a hard-rubber inclosing-case, whereby waste and dispersion of the electric charge take place. The machine thus loses much of its power which might be practically applied. To prevent such waste and 80 dispersion of the electric charge, I make the case *A* and cover *B* of a substance which prevents accumulation of an electric charge on the inclosing-case, and which is yet sufficiently 85 non-conductive to prevent improper discharge of the machine or material weakening of the charge of the machine.

A substance which I have found serviceable for the case and cover is glazed porcelain, which substance prevents the accumulation of 90 an electric charge on the inclosing-case, and which is yet sufficiently non-conductive to prevent discharge or material weakening of the charge of the machine. Waste and dispersion of the electric charge are thus prevented, and as the electricity generated within an inclosure, *A B*, made of such material as porcelain, has no material effect upon such inclosure *A B*, there is no practical waste or leakage of electricity, and the practical working capacity of the machine is increased. Since material such as porcelain is not apt to deteriorate or change from exposure to atmospheric influences or changes in temperature, the interior of the machine will remain 100 thoroughly insulated and protected.

What I claim as new, and desire to secure by Letters Patent, is—

1. An inclosing-case for electrical machines, composed of material which is sufficiently 110 non-conductive to prevent discharging the machine, and which prevents accumulation of an electric charge on the inclosing-case, substantially as set forth.

2. An inclosing-case for friction electric generators, composed of porcelain, and having a removable and replaceable cover of like material, provided with a central orifice for the passage of the axle of the rotating generating-plate, substantially as described.

3. The combination of a case composed of material which is sufficiently non-conductive to prevent discharging an electrical machine, and which prevents accumulation of an electric charge on the inclosing-case, and having 125 a detachable cover of like material provided with a central orifice, with a friction electric generator arranged in said case and having the axle of the rotating generator-plate extending through said opening in the cover, substantially as described.

4. An inclosing-case for electrical machines,

composed of material which is sufficiently non-conductive to prevent discharging the machine, and which prevents accumulation of an electric charge on the inclosing-case, and provided with a detachable cover of like material provided with a central orifice containing a tubular seat, Q, in combination with a friction electric generator arranged in said case and having the axle P of its rotating generating-plate projecting through said orifice, and provided with a lateral shoulder, R, bearing against said tubular seat, substantially as described.

5. The combination of a case for electrical machines, composed of material which is sufficiently non-conductive to prevent discharging the machine, and which prevents accumulation of an electric charge on the inclosing-case, and having a cover of like material provided with 15 a central orifice containing a tubular seat, Q, with a friction electric generator arranged in said case, and having the axle P of its generating-plate projecting through said orifice, and provided with a lateral shoulder, R, and a 20 spring, S, acting on the axle to press its shoulder against the tubular seat, substantially as described.

6. In a friction electric generator, an inclosing-case containing the friction-generator and 25 having its cover provided with a central orifice containing a tubular seat, Q, in combination with the axle P of the rotating generating-plate projecting through said orifice, and provided with a lateral shoulder, R, and extending 30 through said seat, and a spring, S, acting on the axle to press its shoulder against said tubular seat, substantially as described.

7. A friction electric generating-machine

having an inclosing-case of porcelain, substantially as described.

8. The combination, with an inclosing-case for containing a friction electric generator and having a removable cover provided with a central opening for the axle of the rotating generating-plate, of a separate base, E, on 45 which said case rests, provided with projections F, and connections D, engaging said projections and case-cover, to clamp the parts together, substantially as described.

9. The combination, with an inclosing-case 50 for containing a friction electric generator and having a removable cover provided with a central opening for the axle of the rotating generating-plate, of a separate base, E, on which said case rests, provided with projections F, 55 hooks D, engaging over the edge of the said cover, and screws H, connecting the hooks with the projections of the base, substantially as described.

10. An inclosing-case for friction electric 60 generators, composed of material which is sufficiently non-conductive to prevent discharging the machine, and which prevents accumulation of an electric charge on the inclosing-case, and having a removable and replaceable 65 cover of like material provided with a central opening for the passage of the axle which rotates the generating-plate, substantially as described.

In testimony whereof I have hereunto set 70 my hand and seal in the presence of two subscribing witnesses.
